DESIGN FOR A DISPLAY COUNTER

Edward L. Hayes, Detroit, Mich., assignor to
Gratiot Fixture & Supply Co., Detroit, Mich., a
corporation of Michigan

Application April 29, 1938, Serial No. 76,884

Term of patent 7 years

To all whom it may concern:

Be it known that I, Edward L. Hayes, a citizen
of the United States of America and residing at
Detroit, in the county of Wayne and State of
Michigan, have invented a new, original, and
ornamental Design for a Display Counter, of
which the following is a specification, reference
being made to the accompanying drawing, forming
part thereof,

Fig. 1 is a front perspective view of a display
counter showing my new design.

Fig. 2 is an end view.

The rear of the display counter is plain and
conventional.

I claim:

The ornamental design for a display counter,
substantially as shown and described.

EDWARD L. HAYES.
